INVENTOR.

Frank M. Koksma

BY

J. K. Bryant

ATTORNEY.

UNITED STATES PATENT OFFICE.

FRANK M. KOKSMA, OF DOWNS, KANSAS, ASSIGNOR OF ONE-FOURTH TO CHARLES D. JONES, OF DOWNS, KANSAS, AND ONE-FOURTH TO ANTON J. WANDT, OF OSBORNE, KANSAS.

SNOW FENCE.

Application filed August 27, 1927. Serial No. 215,945.

This invention relates to snow fences, and more particularly to an improved barrier or guard by means of which objectionable drifting and banking of snow may be prevented.

A more particular object is to provide an improved fence adapted to be erected along the side of a road or highway at the windward side thereof, whereby objectionable drifting of the snow and banking thereof upon the road is effectively prevented.

A specific object is to provide a snow fence of the above kind which is extremely simple and durable in construction as well as capable of being readily erected or taken down.

Still another object is to provide a snow fence unit so constructed that a plurality of the units thereof may be readily coupled and erected to provide a fence of the desired length.

A still further object is to provide an improved snow fence which may be readily rolled into compact form so as to require a minimum amount of space when stored or during shipment.

Other objects will become apparent as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views:

Figure 1 is a side elevational view of a snow fence constructed in accordance with the present invention, the fence being in operative or erected position;

Figure 2 is an enlarged end elevational view of the device shown in Figure 1;

Figure 3 is a fragmentary plan view of the barrier element of the fence shown in Figure 1 in flat inoperative position;

Figure 4 is an enlarged fragmentary detail view somewhat similar to Figure 3;

Figure 5 is a plan view of one of the guy rods employed for anchoring the barrier element in its operative or set up condition;

Figure 6 is a plan view of one of the stakes employed with the guy rods for an-

choring the barrier element in set up condition, and

Figure 7 is a fragmentary section on line 7-7 of Figure 4.

Referring to the drawings in detail, the present snow fence includes a barrier element or a fence proper composed of a pair of complementary guard members 5 and 6 adapted to be set up in downwardly diverging or inverted V-shaped formation as shown in Figure 2. Each side member consists of a plurality of spaced parallel slats 7 adapted to be arranged in an upright inclined position and connected by horizontal line wires 8 at points adjacent the lower ends of the slats and at spaced points intermediate the ends thereof as shown clearly in Figure 3. The line wires 8 are disposed in pairs with the slats extending between the wires of each pair, and with said wires of each pair twisted together at points between the slats as at 9, whereby the slats are effectively secured in proper position and relation to each other. The slats of one side member 5 are disposed in planes intermediate the slats of the other side member 6 so that the adjacent inner or upper ends of the slats of said side members interfit as clearly disclosed in Figures 3 and 4. These adjacent upper ends of the slat members of both side members 5 and 6 are connected together by further line wires as at 10 which are twisted together at points between the slats for firmly connecting them.

In view of the above it will be seen that the side members 5 and 6 of the barrier element may be readily disposed at any desired angle relative to each other so that said members may be placed at the desired inclination or downwardly diverging relation as shown in Figure 2 when set up for use. When thus set up, each side member of the barrier acts as a brace for the other, and the slats 7 of one side member will serve to intercept the snow which may pass through the spaces between the slats of the other side member of the barrier, thereby effectively causing the snow to pile up at the side of the road instead of drifting on to the road. Further, as the line wires at 10 form a flexible connection between the side members 5

and 6, they may be disposed in flat formation and then the barrier element may be readily rolled up from end to end in compact form for occupying a minimum amount 5 of space during shipment or when in storage.

Means is provided for effectively anchoring the barrier element in its set up or erected position, and for this purpose the ends of 10 the line wires 10 are formed at the opposite ends of the barrier element respectively into a hook 11 and an eye 12. A pair of guy rods 13 are provided, each having an eye 14 at one end and a hook 15 at the other end, 15 while a plurality of stakes 16 are provided, each having an eye 17 at one end and being pointed as at 18 at the other end for being readily driven into the ground. In use, the hook 15 of one guy rod 13 is engaged with 20 the eye 12 at one end of the barrier, while the eye 14 of said guy rod is engaged by the hook 17 of one of the stakes 16 when the latter is driven into the ground. The other guy rod 13 is engaged with the hook 11 at 25 the other end of the barrier element, while the hook 15 of the latter guy rod 13 is engaged by the hook 17 of another stake 16 driven into the ground at the adjacent end of 30 the barrier element. The guy rods 13 are at an inclination from the top of the barrier element longitudinally of the latter so that any longitudinal shifting and upward displacement of the barrier element is effectively prevented. Interlaced with the line wires 35 8 and 10 at spaced points along the barrier intermediate the ends of the latter and adjacent the ends of the members 5 and 6 are cross wires 19 whose ends terminate at the outer or lower ends of the slats 7 of the respective side members 5 and 6 in the form of 40 eyes as at 20. A stake 16 is driven into the ground at each end of each cross wire 19 with its hook 17 engaged with the adjacent eye 20 of said cross wire, and in this way 45 lateral displacement or tilting of the barrier element is effectively prevented while additional prevention is had against any other shifting of the barrier element which might take place.

50 In view of the above it will be seen that the barrier element and anchoring means therefor are extremely simple and durable in construction, and the fence is adapted to be conveniently erected or taken down within 55 a minimum amount of time and with a minimum expenditure of labor.

Minor changes may be made without departing from the spirit and scope of the invention as claimed.

60 What I claim as new is:—

1. In a snow fence, a barrier element comprising side members connected at the top and adapted to be set up in downwardly diverging relation, each side member embodying spaced cross slats connected by spaced

line wires, the slats of one side member being disposed between the slats of the other side member.

2. In a snow fence, a barrier element comprising side members connected at the top 70 and adapted to be set up in downwardly diverging relation, each side member embodying spaced cross slats connected by spaced line wires, the slats of one side member being disposed between the slats of the 75 other side member, and further line wires connecting the upper ends of the slats of both side members whereby the latter are flexibly connected to permit the barrier element to be placed in flat form and rolled 80 into compact form when not in use.

3. In a snow fence, a barrier element comprising side members connected at the top and adapted to be set up in downwardly diverging relation, each side member embodying spaced cross slats connected by spaced line wires, and cross wires interlaced with the line wires at spaced points along the barrier element, said cross wires having ends terminating at the lower ends of the slats 90 of the side members, and stakes engageable with the ends of the cross wires to anchor the barrier element on the ground in set up condition.

4. In a snow fence, a barrier element comprising side members connected at the top and adapted to be set up in downwardly diverging relation, each side member embodying spaced cross slats connected by spaced line wires, and further line wires connecting 100 the upper ends of the slats of one side member with the upper ends of the slats of the other side member, said further line wires terminating in a hook at one end of the barrier element and an eye at the other end 105 thereof to facilitate connection of a plurality of barrier elements in end to end relation.

5. In a snow fence, a barrier element comprising side members connected at the top and adapted to be set up in downwardly 110 diverging relation, each side member embodying spaced cross slats connected by spaced line wires, and cross wires interlaced with the line wires at spaced points along the barrier element, said cross wires having ends terminating at the lower ends of the slats of the side members, and stakes engageable with the ends of the cross wires to anchor the barrier element on the ground in set up condition, further line wires connecting the upper ends of the slats of one 115 side member with the upper end of the slats of the other side member, guy rods engageable with the ends of said further line wires at the ends of the barrier element, and stakes for anchoring the guy rods to the ground.

In testimony whereof I affix my signature.

FRANK M. KOKSMA.
